MACHINE FOR USE IN THE MANUFACTURE
OF PREWELT SHOESEric A. Holmgren, Beverly, Mass., assignor to
United Shoe Machinery Corporation, Flemington, N. J., a corporation of New Jersey

Application November 26, 1942, Serial No. 466,975

31 Claims. (Cl. 12—1)

1

This invention relates to machines for use in the manufacture of prewelt shoes and is herein illustrated in its application to machines for use in practicing off-the-last methods of prewelt shoemaking such, for example, as the method set forth in my copending application for United States Letters Patent Serial No. 557,999, filed October 10, 1944.

Prewelt shoes in the range of children's sizes are found in the lower price brackets and manufacturers of this type of children's shoe operate on a very small margin of profit and are constantly seeking improvements in their methods and machines calculated to effect economies in the cost of manufacture. One of the major items in the cost of prewelt shoe manufacture is the initial cost of the lasts on which the uppers are made and the continual expense of maintaining, repairing, storing and sorting the lasts. In the manufacture of prewelt shoes, this item of expense is a much larger proportion of the total manufacturing cost than in the production of higher priced footwear. Thus, it will be understood that any commercially practicable system of making prewelt shoes which obviates the use of the last will effect a substantial economy in the manufacturing cost, if the proposed method does not involve excessive labor or machine costs.

It is an object of the present invention to provide a simple and efficient machine for use in shaping prewelt uppers off the last and adapted to be employed in the practice of the method of making prewelt shoes set forth in my copending application above referred to.

With the above objects in view, the invention in one aspect thereof consists in the provision in a machine for use in the manufacture of prewelt shoes of an inner form which takes the place of the last, said form being reversible for operation on right and left uppers, and means for holding said form against free upward movement. The illustrated form supports a prewelt upper by its welted margin for the operation of wiping means which operates to bring the welted margin in over the margin of said form and to hold it in overwiped position while it is attached to a sole.

In another aspect thereof, the invention consists in the combination in a machine for use in the manufacture of prewelt shoes of an inner form for supporting a prewelt upper by its welted margin, said form being reversible for operation on right and left uppers, and identical wipers operable alternatively on right and left uppers

2

to wipe the welted margin at opposite sides of the upper in over the margin of said form. It will be understood that the provision of wipers operable on both right and left uppers reduces the changing of wipers and also the number of wipers required for operation on a given run of shoe sizes. In order to provide wipers adapted to operate on a substantial run of sizes, the illustrated machine, in accordance with a further feature of the invention is provided with wiping means including a wiper constructed and arranged to swing about an axis intersecting its wiping edge to the end that the wiper may adjust itself to varying edge contours. The illustrated wiper is mounted to turn freely on its axis and has a sufficient range of turning movement to adapt it to operate alternatively on right and left uppers. It will be understood that the wiping edge has a shape or curvature generally common to the peripheral contour of right and left shoes in the run of sizes on which the wiper is intended to operate. In the illustrated machine, one such wiper operates on a run of children's sizes from 2 to 9, inclusive.

In accordance with a further feature of the invention, the illustrated machine is provided with a wiper assembly including a pair of side wipers having a fixed orientation and a pair of forepart wipers constructed and arranged to be oriented by their engagement with the upper. In addition to the side wipers and the forepart wipers, the illustrated assembly includes a pair of shank wipers and a toe wiper constructed and arranged to overwipe the entire toe portion of the welted margin. In accordance with another feature of the invention, the illustrated toe wiper is reversible for operation on right and left uppers by turning it about an axis coinciding with the longitudinal median line of a shoe in the machine.

In order to provide a progressive wiping action of said forepart wipers, said wipers, in accordance with a feature of the invention, are normally so oriented that their rear end portions enter the welt crease in advance of the forward portions of the wipers, said wipers swinging inwardly about their rear end portions to complete the overwiping movement. The illustrated side wipers are constructed and arranged to operate on that portion of the upper extending rearwardly from the shank wipers and have straight wiping edges which operate on as much of the welted margin as lies within the range of their overwiping movement. Inasmuch as the heel portion of the upper is, preferably, molded prior to the operation of the illustrated machine, it is

deemed unnecessary to provide means for overwiping the curved heel end portion of the welted margin. It will be understood that due to slight differences in the line of the welted upper at opposite sides of the rear part of the shoe, the wiping edges of the side wipers will not be perfectly aligned with the inner form on which the upper is mounted but such differences as exist are relatively slight and the use of narrow shank wipers taken in conjunction with the relative rigidity of the welt enables the wipers to effect a substantially uniform overwiping of the welted margin.

In order to insure the entrance of the wipers into the welt crease, the illustrated upper-supporting form, in accordance with a further feature of the invention, is initially slightly elevated so that the wipers engage the upper along a line slightly below the welt crease, and means is provided for moving said form downwardly so that the wipers register with the welt crease. During the downward movement of said form, the wipers are held against the upper under a relatively light pressure and, after the wipers come into registration with the welt crease, relatively heavy pressure is imparted thereto to complete their overwiping movement.

These and other features of the invention will now be described with reference to the accompanying drawings and pointed out in the appended claims.

In the drawings,

Fig. 1 is a plan view illustrating the work-supporting plate and the wiper assembly with the wipers in their advanced positions, portions of the wipers being broken away;

Fig. 2 is a plan view similar to Fig. 1 showing the wipers in relation to a work-supporting plate of the smallest size in the run of sizes on which the wipers operate;

Fig. 3 is a front elevation, partly broken away, illustrating a machine embodying the features of the present invention;

Fig. 4 is a sectional elevation somewhat enlarged taken substantially on the line IV—IV of Fig. 12;

Fig. 5 is a detail sectional view taken on the line V—V of Fig. 4;

Fig. 6 is a sectional view taken on the line VI—VI of Fig. 4;

Fig. 7 is a side elevation with parts of the frame broken away and the machine table shown in section;

Fig. 8 is a section taken on the line VIII—VIII of Fig. 7;

Fig. 9 is a sectional elevation taken substantially on the line IX—IX of Fig. 7;

Figs. 10 and 11 are side elevations illustrating the shank wipers in successive stages in their operation on a shoe illustrated in cross section;

Fig. 12 is a plan view showing the wipers at the completion of their operation;

Fig. 13 is a section taken on the line XIII—XIII of Fig. 12;

Fig. 14 is a perspective view illustrating the work-supporting plate, somewhat enlarged;

Fig. 15 is a front elevation illustrating an alternative work-supporting mechanism and an upper thereon shown in longitudinal section;

Fig. 16 is a rear elevation of the mechanism illustrated in Fig. 15, the work-supporting parts being shown in central longitudinal section; and

Fig. 17 is a plan view, partly in section, illustrating the work-supporting members shown in Figs. 15 and 16.

Referring to Fig. 1, the illustrated machine is provided with a plurality of wipers constructed and arranged to enter the welt crease of a pre-welt upper and to wipe the welted margin inwardly over the margin of a sole-shaped form corresponding in size to the uppers to be operated upon, the form 20 illustrated in Fig. 1 corresponding to a juvenile size 9 upper. The illustrated form is a wooden plate so constructed that it may be reversed for operation on both right and left uppers. In order that the form may serve to impart the desired convex shape to the shoe bottom the top and bottom surfaces of the form may be made convex to correspond generally to the shape of the sole face of a last. For convenience of manufacture, the shape of the sole face of a last is simulated in the illustrated form by providing a flat bevel 21 (Figs. 9 and 14) in its marginal portion. The opposite side portions of the upper are wiped inwardly over the form 20 by side wipers 22, narrow shank wipers 24, and forepart wipers 26, while the toe portion of the upper is overwiped by a single toe wiper 28. The wipers 22, 24, and 26 operate on a run of sizes from 2 to 9, while the toe wiper 28 operates only on two sizes, that is, 8 and 9. In operating on size 9, the toe wiper and the forepart wipers in their respective overwiped positions are spaced apart from each other about one-sixth of an inch, as shown in Fig. 1. In operating on a size 8 upper, the toe wiper and the forepart wipers would be substantially contiguous. In Fig. 2, the wipers 22, 24 and 26 are shown in their respective overwiped positions on a form 30 corresponding to a size 2 upper and a toe wiper 32 is also shown in its overwiped position, said toe wiper being constructed for operation on upper sizes 2 and 3. It will be seen that the toe wiper 32 in its overwiped position illustrated in Fig. 40 is substantially contiguous to the forepart wipers 26.

Referring now to Fig. 3, each side wiper 22 is secured by headed screws 34 to the crosshead of a T-shaped bar 36 which in turn is secured to an arm 38, the lower portion of which is pivotally mounted on a cross-shaft 40 secured in blocks 42 extending upwardly from a table 44 secured to the upper portion of a standard 46. Each shank wiper 24 is an angular plate (Figs. 3 and 10), the downward extending portion of which is secured by headed screws 48 to the upper portion of a bar 50, the lower portion of which is secured to an arm 52 pivotally mounted at its lower end on the cross-shaft 40. Thus, it will be seen that the side wipers 22 and the shank wipers 24 advance into operating position in an arcuate path the center of curvature of which coincides with the cross-shaft 40. When the wipers come into the welt crease, as shown in Fig. 11, the wiper bars are substantially vertical and during the actual overwiping movement, which is not more than a quarter of an inch in extent, the wipers advance in a substantially horizontal direction widthwise of the upper. It will be understood that the side wipers and the shank wipers during their overwiping movement are held in fixed relation to the wiper bars, said bars in turn being held in fixed relation to their carrying arms and, consequently, said wipers maintain a substantially fixed orientation during their overwiping movement. Each of the forepart wipers 26, on the other hand, swings during its overwiping movement about a substantially vertical axis identified by a dot 54 in Figs. 1 and 2, said axis bisecting the wiping edge of the wiper.

The forepart wipers advance with their rounded corner portions 56 foremost and, after said rounded portions come into engagement with the welted margin of the upper, the forepart wipers, during the continued inward movement of their carrier arms, swing about said rounded corners as the wipers are oriented with relation to the welted margin of the upper. It will be understood that the wipers turn on their axes 54 during their inward movement. Referring to Figs. 3, 7 and 12, each of the illustrated forepart wipers 26 is secured by a headed screw 58 and a dowel pin 60 to the crosshead of a T-shaped bar 62. The bar 62 is mounted for swiveling movement about the axis identified by the dot 54 on an arm 64 which is pivotally mounted at its lower portion on the cross-shaft 40. For swiveling the bar 62 on the arm 64 said bar has ears 66 which register with ears 68 on the arm, a fulcrum pin 70 extending through the adjacent portions of said ears. Each forepart wiper is normally oriented with its rounded corner portion foremost by a torsion spring 72 surrounding the pin 70 and positioned between the ears 68, one end of said spring bearing against the arm 64 and the other end against the bar 62. The spring 72 urges the bar 62 in a direction such that a stop screw 74 adjustably mounted in a plate 76 secured to the lower portion of the bar 62 is normally held against the arm 64.

The toe wiper 28 (Figs. 4 and 6) is removably mounted in a plate or holder 78 which has a deep groove extending inwardly from its forward edge face for the reception of the toe wiper. The toe wiper is inserted into its holder by movement widthwise thereof through the groove in the wiper holder, the path of movement of the wiper relatively to its holder being determined by the registration of a pin 80 in the holder with a groove 82 extending widthwise of the wiper from a side edge to its central portion. The widthwise position of the wiper in the holder is determined and maintained by a headed spring-pressed pin 84 mounted in a hollow hub 86 of the wiper holder 78 and arranged to enter a notch 87 in the wiper. The notch is made slightly wider than the diameter of the pin to enable the wiper to be adjusted widthwise by its engagement with the upper. The hub 86 is mounted in a bore in the upper end portion of an arm 88 for turning movement about an axis which coincides with the longitudinal median line of a shoe in the machine when the wiper is in its overwiping position. The wiper assembly is turned 180° in the arm 88 to adjust the wiper to operate alternatively on right and left uppers. For positioning the wiper lengthwise thereof relatively to the arm 88, the inner portion of the hub 86 has a flange 90 which engages the inner surface of the arm. For holding the wiper against turning in the arm 88, the cross-head of a T-shaped pin 92 (Fig. 5) alternatively engages slotted portions 94 of the hub 86. The pin 92 is slidably mounted in a bore in a plate 96 secured to the inner surface of the arm 88 and is urged upwardly by a spring 98 in said bore. It will be seen from Fig. 4 that the pin 92 also serves to maintain the lengthwise position of the toe wiper by holding the flange 90 against the arm 88. For mounting the arm 88 its offset lower portion 100 is connected by short, parallel-motion links 102 to an arm 104 having an extension 106, the end portion of which is pivotally mounted between ears 108 (Fig. 7) extending upwardly from the machine table 44. The arm 88 is longitudinally positioned relatively to the arm 104 be-

tween a stop screw 110 in the lower end portion of the arm 88 arranged to engage an extension 112 of the arm 104 and a spring-pressed pin 114 mounted in a bore in the arm 100, said arm having a recess 116 which receives the extension 112 and into which the screw 110 and the pin 114 project.

Referring now to Fig. 13, for arresting the overwiping movement of the side wipers 22, each of the wiper-carrying bars 36 carries an abutment member or block 118 in a groove in its upper end portion, the convex inner end 120 of said block being arranged to engage the periphery of a shoe upper on the form 20. It will be understood that the block 118 arrests the advancement of the bar 36 and determines the extent of overwipe of the side wiper 22. In order to vary the extent of overwipe of the side wipers to meet the requirements of the particular type of upper to be operated upon a headed screw 122 is mounted in the bar 36 and provided with a flange 124 which is seated in a suitable groove in the block 118. Inasmuch as the side wipers 22 and the shank wipers 24 are advanced by a common actuator the blocks 118 also serve to arrest the overwiping movement of said shank wipers. For arresting the overwiping movement of the forepart wipers 26 (Fig. 12) each bar 62 has mounted in its upper end portion an abutment member or block 126 similar to the block 118 and a block adjusting screw 128 having a flanged head which operates in the block 126 in the same manner as the screw 122 above described.

Referring to Fig. 9, the illustrated form 20 rests on the upper surface of the head 130 of a bar 132 and is positioned relatively to the wipers by a headed pin 134 projecting upwardly from the head 130 and extending through a hole 136 in the form 20, said hole being large enough to permit the head of the pin 134 to pass through it. The head of the pin 134 is seated in an offset counterbore 138 (Fig. 1) extending toewards from the hole 136, the diameter of the counterbore being the same as the diameter of the head of the pin 134. The rear portion of the form 20 is positioned by a headed pin 140 (Fig. 9) projecting upwardly from an arm 142 and extending through a hole 144, the head of the pin being seated in a heelwardly offset counterbore 145 (Fig. 1) in the rear portion of the form 20. The arm 142 is pivoted at 146 to a downwardly extending portion of the head 130 and is urged in a counterclockwise direction, as seen in Fig. 9, by a spring 148 mounted in a bore in the head 130. The spring 148 urges the pin 140 heelwardly and away from the pin 134, thus maintaining the position of said pins relative to the form 20 illustrated in Fig. 9 and holding the form in a predetermined central position in the head of the machine. In this position the longitudinal median line of the form is in alignment with the center of the hub 86 of the toe wiper holder 78 when the toe wiper is in its advanced position. The illustrated form 20 may be readily removed from its supporting bar 132 to be replaced by another form of a different size, or it may be inverted when changing from right to left uppers, or vice versa, by merely pressing the upper portion of the arm 142 to the right, as seen in Fig. 9, until the heads of the pins 134 and 140 are brought into alignment with the holes 136 and 144, whereupon the form 20 can be lifted off the head of the bar 132. Upon releasing the arm 142 after the form 20 has been thus removed from the bar 132, said arm is swung in a counterclockwise direction by the spring 148 and comes

to rest when an inward extension 150 of the lower portion of said arm engages the bar 132. In order that the headed pins 134 and 140 may operate on the form 20 in the manner described after the form has been inverted, the counterbores 138 and 145 are reproduced in the bottom of the form, as shown in Figs. 9 and 14. The bar 132 is slidably mounted in a channel rail 152 projecting upwardly from the table 44 and is held seated in said channel rail by headed screws 154 mounted in the web of said rail and arranged to extend through vertical slots 156 in the bar 132. The form 20 is yieldingly held at the limit of its upward movements by a spring 158 one end of which engages a pin 160 in the bar 132 and the other end of which engages a fixed pin 162. The spring holds the bar 132 in its position illustrated in Fig. 9, the bar being located by the engagement of the lower end walls of the slots 156 with the screws 154.

For operating the toe wiper 28 a treadle 164 (Fig. 3) is secured to a cross-shaft 166 in the base of the standard 46 and is connected by a link 168 to the forward end portion of a rocker lever 170 secured to a rockshaft 172. Pivotedly mounted on trunnion pins in the bifurcated rear portion of the rocker lever 170 (Fig. 7) is a block 174 which is bored to receive in sliding engagement a rod 176 the upper end portion of which has a universal connection to the lower end of a link 178 (Fig. 3) which is pivoted at its upper end to the lower portion of the arm 104 which carries the toe wiper assembly. For stabilizing the link 178 an arm 180 is pivotally mounted at one end on a bracket 182 extending downwardly from the table 44 and at its opposite end is pivoted to the link 178 in parallel relation to the extension 106 of the arm 104. Upon depression of the treadle 164 the rocker lever 170 imparts upward movement to the rod 176 through a spring 184 surrounding said rod and confined between a collar 186 on said rod and the block 174. The upward movement of the rod 176 operates through the mechanism above described to bring the toe wiper 28 into engagement with the outer surface of a prewelted upper 188 on the form 20 at a point slightly below the welt 189. After the toe wiper 28 engages the upper, the treadle 164 is further depressed to a small extent to compress the spring 184 slightly thus to urge the toe wiper under light pressure against the upper. Thereupon a latch bar 190 (Fig. 7), freely mounted on a cross-shaft 192, engages a pin 194 projected laterally from an arm 196 fixed to the cross-shaft 166 to hold the treadle 164 against upward movement. The operator now depresses a treadle 198 to complete the operation of the machine. The treadle 198 operates first to bring the side wipers 22, shank wipers 24, and forepart wipers 26 into engagement with the upper under relatively light pressure, then imparts downward movement to the bar 132 to bring the upper 188 into position to receive the wipers within the welt crease, and finally imparts relatively heavy pressure to the side wipers, the shank wipers and the forepart wipers, and also to the toe wipers, to cause them to wipe the welted margin of the upper in over the form 20. For actuating the side wipers, shank wipers, and forepart wipers, the treadle 198 is connected to a rod 200 which, as shown in Fig. 9, extends upwardly through a hole in the table 44 and carries near its upper end a plate 202, said plate having a hub 204 which is pinned to the rod 200. Six vertical rods 206 (Figs. 3 and 9) extend upwardly through

holes in the plate 202, there being three of said rods at each side of the plate arranged to actuate the wipers. The upper portion of each rod 206 extends through an opening in the table 44 and is pivoted to a short downward extension of an arm 228 (Fig. 7) secured to one of the wiper-carrying arms. The pivotal connection of each rod 206 to its arm 228 is so positioned relatively to the shaft 40 that the rod 206 moves downwardly with the least possible horizontal component of movement of its upper end portion. Each rod is supported by the engagement of a collar 208 fixed thereto with the top of the plate 202. Referring to Fig. 8, each rod 206 carries a light spring 210 and a relatively heavy spring 216 which operate in sequence by downward movement of the plate 202 first to maintain slight pressure of the wipers against the upper during the downward movement of the work-supporting form 20, and, finally, to apply relatively heavy overwiping pressure to the wipers. As shown in Fig. 8, the light spring 210 surrounds the rod 206 and is confined between a sleeve 212 slidably mounted on the rod above said spring and a nut 214 below said spring. The relatively heavy spring 216 surrounds the lower portion of the rod 206 and is confined between a washer 218 which abuts a nut 220 and a washer 222 (Fig. 7) supported by a nut 224. A sleeve 226 surrounds the light spring 210 and is centered by the sleeve 212 and supported by the washer 218. It will be understood that there are six assemblies such as that illustrated in Fig. 8, one for each of the rods 206. During the downward movement of the plate 202 by the treadle 198, said assemblies move downwardly as a unit until the wipers engage the shoe and arrest the downward movement of the rods 206, whereupon further downward movement of the plate 202 compresses the light springs 210 until the bottom surface of said plate engages the upper end of each sleeve 226. Further downward movement of the plate 202 operates through said sleeves to compress the heavy springs 216. The downward movement of the work-supporting form 20 is timed to occur when the wipers are under the light pressure of the springs 210. Upon the completion of the downward movement of the work-supporting form, the heavy spring 216 comes into action to apply relatively heavy pressure to the wipers. For imparting downward movement to the bar 132, which supports the form 20, the rod 200 is provided with means constructed and arranged to operate against an L-shaped bar 230 (Fig. 9) secured to the lower portion of the bar 132 by headed screws 232, said bar having a horizontal bifurcated end portion through which extends the rod 200. For imparting downward movement to the bar 230, a washer 234 is freely mounted on said rod and supported by a collar 233 secured to said rod. Upon completion of the inward movement of the wipers, the washer 234 engages the bar 230 and through the action of a spring 238 surrounding the rod 200 moves the bar 132 downwardly until it is arrested by the engagement of a stop screw 236 carried by said bar with the upper end of the channel rail 152. Further depressions of the treadle 198 after the downward movement of the bar 132 has been arrested moves the rod 200 downwardly relatively to the L-shaped bar 230 and advances the wipers under the relatively heavy pressure of the springs 216 to perform the overwiping operation. It should be noted that the final pressure against the wipers, while it is relatively heavy

as compared with the initial pressure, is not heavy enough to apply any considerable force against the welted margin of the upper, said final pressure being no more than is required to insure the complete overwiping of the side portions of the upper. While the treadle 198 is applying relatively heavy pressure to the wipers at opposite sides of the shoe to effect the overwiping operation a screw 240 (Fig. 7) carried by an angle plate 242 secured to the treadle engages and imparts downward movement to the arm 196 thereby swinging the rocker lever 170 in a counterclockwise direction, as seen in Fig. 7, to increase the compression of the spring 184 thus to insure a complete overwiping movement of the toe wiper. Upon the completion of the downward movement of the treadle 198, a latch bar 244, identical to the latch bar 190, engages a pin on said treadle to hold the treadle against the return movement. It will be understood that the latch bars 190 and 244 operate to retain the wipers in their overwiped positions after the operator takes his foot off the treadle. While the wipers are so held, a sole, usually an outsole, is cement-attached to the welt and thereupon the latch bars are released to permit the return of the operating parts to their rest positions and to release the upper for removal from the machine. For so releasing the latch bars, the illustrated machine is provided with a hand lever 246 (Fig. 3) secured to the left end portion of the cross-shaft 192 to the central portion of which there is secured an arm 250 (Fig. 7) which carries in its lower end a pin 252 which engages the two latch bars when the hand lever 246 is swung rearwardly, thus disengaging the latch bars from their pins and permitting the return of the operating parts to their respective rest positions by the operation of suitable treadle springs.

In Figs. 15, 16 and 17 there is illustrated an alternative work-supporting mechanism comprising a forward plate or form 254 which supports the forepart and shank portion of a prewelt upper by its welted margin and a heel form or block 256 which has substantially the surface contour of the heel end portion of a last. Said forms are relatively movable lengthwise of the upper into a contracted position in which they are slightly shorter in over-all length than prewelt uppers to be mounted thereon. Upon relative lengthwise movement away from each other, said forms fill and slightly tension the upper, as shown in Fig. 15, and the heel block imparts the desired shape to the heel portion of the upper. For causing the heel block 256 to register at all times with the rear portion of the form 254, said form has a heelward extension 258 (Fig. 17), the opposite side walls of which engage the side walls of a recess 260 in the heel block. Said recess is covered by a sole plate 262 (Fig. 15) which has a forwardly extending margin which bridges the gap between the block 256 and the form 254 and is seated in a shallow recess 264 (Fig. 17) in the rear portion of the form 254. Said form is mounted on the head 266 of a bar 268 similar to the bar 132 which supports the form 20. As in the case of the bar 132, the bar 268 has mounted on its head 266 a headed pin 270 which extends through a counterbored hole in the form 254 and said bar carries a swinging arm 272 which has a similar pin 274 extending upwardly therefrom, said pins operating in counterbored holes in the form 254, as in the form-supporting mechanism illustrated in Fig. 9. The

heel block 256 is mounted on a post 276 extending upwardly from a slide 278 mounted on a heelward extension 280 of the bar 268. For positioning the heel block on said post, a tongue 282 extends upwardly therefrom for engagement within a groove 284 extending heelwardly from the central portion of the recess 260, said tongue being held seated within the groove in the heel block by a crosspin 286 which engages the forward edge face of said tongue. For operating the slide 278 to move the heel block toward and from the form 254, a hand lever 288 is pivoted at 290 on the extension 280. Cooperating with said hand lever is a triangular plate 292 the narrow end portion of which is pivoted on a headed screw 294 mounted in the slide 278. The wide end portion of the plate 292 is provided with three holes 296 arranged in a straight line extending upwardly at an inclination away from the heel block 256, said holes receiving alternatively a headed pin 298 which also extends through a hole in the central portion of the hand lever 288 to enable said plate 292 to serve as a link connecting the hand lever to the slide 278. A set screw 300 in the hand lever holds the headed pin in position. The hand lever is movable between two extreme positions determined by the engagement of a spring-pressed pin 302 projecting from the bifurcated end portion of said hand lever with shoulders 304 and 306 in the extension 280. It will be understood that in the raised position of the hand lever, the form 254 and heel block 256 are in their contracted position ready to receive an upper to be operated upon and, in the lower position of the hand lever illustrated in Figs. 15 and 16, the work-supporting parts are expanded to tension the upper lengthwise by straightening of the inverted toggle formed by the plate 292 and the portion of the lever 288 between the pivots 290 and 298. It will be understood that the spring-pressed pin 302 acting against the shouldered portions of the extension 280 yieldingly holds the hand lever in either of its extreme positions. The holes 296 in the triangular plate 292 permit an adjustment of the work supports for operation on three sizes of uppers. Before operating on uppers in sizes outside the range of adjustment of the plate 292, the form 254 is removed and a similar form of a suitable size is substituted. The heel block operates on all sizes within the run of sizes on which the side, shank and forepart wipers operate and, consequently, in the usual course of shoe manufacture will seldom be removed from the post 276 and a different size of heel block substituted.

In the operation of the machine in practicing the method set forth in my copending application hereinbefore referred to, a prewelt upper, for example, the upper 188 illustrated in Fig. 3, is loosely mounted on the form 20 with the welted margin at the toe end of the upper positioned adjacent to the upper surface of the form and with the rear portion of the upper so located that the heel end of the form engages the upper substantially midway between its welted margin and its top edge. With the upper thus loosely positioned on the form, the operator depresses the treadle 164 to bring the toe wiper 28 into engagement with the toe portion of the upper slightly below the welt and to press the wiper lightly against the upper. Upon completion of the downward movement of the treadle, the latch bar 190 (Fig. 7) is swung to the right by a spring 320 bringing its shouldered lower end portion into

latching engagement with the pin 194 on the arm 196. The operator now presses the heel portion of the upper downwardly until the welted margin, all around the upper, lies adjacent to the upper surface of the form 20. The toe wiper 28, underlying the welt 188 at the toe end of the upper, will prevent the toe portion of the upper from being pulled away from the plate 20 by the lengthwise tension applied to the upper to bring it into horizontal position on the form 20. The treadle 198 is now depressed first to bring the wipers at opposite sides of the upper into engagement with the upper under light spring pressure, then to move the work support together with the upper 188 mounted thereon downwardly until the wipers register with the welt crease in the upper, and, finally, to advance the wiper into the welt crease under relatively heavy spring pressure to complete the overwiping operation. Upon completion of the downward movement of the treadle 198, the latch bar 244 locks the treadle against return movement thus retaining the wipers in their respective overwiped positions in which they support the outward extension of the welt while a sole is cement-attached to the bottom face of the welt.

When the illustrated machine is provided with work-supporting mechanism illustrated in Figs. 15, 16 and 17, the method of handling the upper differs from the method above described in that the upper is in the first instance mounted in a horizontal position on the form 254 and the heel block 256, as shown in Fig. 15. To facilitate so mounting the upper, the two-part work support is initially contracted lengthwise thereof, the heel block 256 being positioned at the limit of its movement toward the form 254. After the upper is mounted on the work-supporting members and the toe wiper has been brought to bear against the toe portion of the upper, the hand lever 288 is moved downwardly to move the heel block away from the form 254, thus imparting lengthwise tension to the upper and holding it for the further operation of the wipers.

In Figs. 10 and 11 the illustrated machine is shown in successive stages in its operation on a prewelt shoe having an insole and a filler, and an outsole initially cement-attached to the welt and filler. In the manufacture of such shoes, a filler 310 is cement-attached to an insole 312 and the assembly thus provided is mounted on the form 20, as shown in Fig. 10, and the wipers operate to wipe the welted margin inwardly over the exposed margin of the insole and into contact with the edge face of the filler. While the outward extension of the welt is supported by the wipers, an outsole 314 (Fig. 11) is cement-attached to the welt and filler.

It will be understood that the utility of the illustrated machine is not limited to its illustrated use in the manufacture of prewelt shoes having an insole, a filler and an outsole attached directly to the welt but may be employed in the manufacture of all types of prewelt shoes in which the welted margin is wiped inwardly to position it for attachment to a sole. It will also be understood that while the welted margin in the process herein illustrated is secured in over-wiped position by the cement attachment of the outsole thereto, it is immaterial to the present invention what process is employed to secure the welted margin in overwiped position. It could, if desired, be secured by cement or by suitable fastenings to the insole or the filler or to both insole and filler in which case the attachment of the outsole could take

place after the shoe is removed from the illustrated machine.

Upon completion of the operation of the machine and the manual operations performed while the upper is held in over-wiped position, the hand lever 246 (Figs. 3 and 7) is operated to disengage the latch bars 190 and 244 from the parts on which they operate whereupon a spring 316 operating on the arm 196 raises the treadle 164 and a spring 318 raises the treadle 198 returning the wipers to their open or outspread position illustrated in Fig. 3 and leaving the shoe free to be removed from the form 20.

Preferably the prewelt upper is prepared for the operation of the illustrated machine by pre-shaping or expanding the end portions of the upper and by so shaping or arranging the welted margin that the welt lies in substantially sole-attaching position with its outward extension standing away from the bottom margin of the upper and providing an open welt crease adapted to receive the wipers of the illustrated machine, and the inward extensions of the welt and upper arranged to overlie the margin of the upper-supporting form of the illustrated machine, or an insole mounted thereon. While it is within the scope of the present invention to perform the preshaping operations by any known means, I prefer to employ for this purpose a machine such as that illustrated in United States Letters Patent No. 2,359,762, granted October 10, 1944, on an application filed in my name.

Having thus described my invention, what I claim as new and desire to secure by Letters Patent of the United States is:

1. In a machine for use in the manufacture of prewelt shoes, an inner form for supporting a prewelt upper by its welted margin, said form being reversible for operation on right and left uppers, and means for holding said inner form against free upward movement.

2. In a machine for use in the manufacture of prewelt shoes, an inner form for supporting a prewelt upper by engagement with the welted margin about the entire periphery of the upper, said form being reversible for operation on right and left uppers, and disengageable means for holding said inner form against free upward movement.

3. In a machine for use in the manufacture of prewelt shoes, an inner heel form and an inner forepart form for supporting the forepart and shank portion of a prewelt upper by its welted margin, said inner forepart form being reversible for operation on right and left uppers, and disengageable means for holding said inner form against free upward movement.

4. In a machine for use in the manufacture of prewelt shoes, an inner form for supporting a prewelt upper by its welted margin, said form having a surface characterized by a raised central portion, said surface corresponding generally to the convex sole face of a last, and means on which said form is reversibly mounted for operation on right and left uppers.

5. In a machine for use in the manufacture of prewelt shoes, a heel form for supporting the heel portion of a prewelt upper, an inner form for supporting the forepart and the shank portion of a prewelt upper, said inner form having upper and lower surfaces characterized by raised central portions, said surfaces corresponding generally to the convex sole face of a last, and means on which said inner form is reversibly mounted for operation on right and left uppers.

6. In a machine for use in the manufacture of prewelt shoes, a heel form for supporting the heel portion of a prewelt upper, an inner form for supporting the forepart and the shank portion of a prewelt upper, said inner form having upper and lower surfaces characterized by raised central portions, said surfaces corresponding generally to the convex sole face of a last, means on which said inner form is reversibly mounted for operation on right and left uppers, and means for effecting relative movement of the heel form and said inner form lengthwise of an upper supported thereon.

7. In a machine for use in the manufacture of prewelt shoes, an inner form for supporting a prewelt upper by its welted margin, said form being reversible for operation on right and left uppers, and means for wiping the welted margin in over the margin of said form.

8. In a machine for use in the manufacture of prewelt shoes, an inner form for supporting a prewelt upper by its welted margin, said form being reversible for operation on right and left uppers, and identical wipers operable alternatively on right and left uppers to wipe the welted margin at opposite sides of the upper in over the margin of said form.

9. In a machine for use in the manufacture of prewelt shoes, an inner form constructed and arranged to support a prewelt upper by its welted margin, said form being reversible for operation on right and left uppers, and means for wiping the welted margin in over said form including a wiper constructed and arranged to turn about an axis intersecting its wiping edge.

10. In a machine for use in the manufacture of prewelt shoes, an inner form constructed and arranged to support a prewelt upper by its welted margin, and means for wiping the welted margin in over said form including a wiper constructed and arranged to turn about an axis substantially bisecting its wiping edge.

11. In a machine for use in the manufacture of prewelt shoes, an inner form constructed and arranged to support a prewelt upper by its welted margin, a wiper for wiping a portion of the welted margin in over said form, a carrier on which said wiper is mounted for turning movement about an axis intersecting its wiping edge, said wiper being mounted to move freely about said axis to adjust itself to the periphery of said inner form.

12. In a machine for use in the manufacture of prewelt shoes, an inner form constructed and arranged to support a prewelt upper by its welted margin, a forepart wiper mounted to turn on an axis intersecting its wiping edge, said wiper having a range of turning movement sufficient to adapt it to operate alternatively on right and left uppers.

13. In a machine for use in the manufacture of prewelt shoes, a plurality of wipers constructed and arranged to operate within the welt crease of a prewelt upper, said wipers comprising a toe wiper constructed and arranged to be inverted for operation on both right and left uppers, and a pair of forepart wipers constructed and arranged to be oriented by their engagement with the upper.

14. In a machine for use in the manufacture of prewelt shoes, a pair of identical forepart wipers mounted to swing about axes intersecting their wiping edges thereby to effect their orientation relatively to the upper, and a toe wiper constructed and arranged to overwipe substantially all of that portion of the welted margin extending toewards from the forepart wipers, said toe wiper

being reversible for operation on right and left uppers.

15. In a machine for use in the manufacture of prewelt shoes, a plurality of wipers constructed and arranged to operate within the welt crease of a prewelt upper, said wipers including a pair of side wipers having a fixed orientation and a pair of forepart wipers constructed and arranged to be oriented by their engagement with the upper.

16. In a machine for use in the manufacture of prewelt shoes, a plurality of wipers constructed and arranged to operate within the welt crease of a prewelt upper including side wipers and shank wipers each having a fixed orientation, and forepart wipers constructed and arranged to be oriented by their engagement within the welt crease.

17. In a machine for use in the manufacture of prewelt shoes, a plurality of wipers constructed and arranged to operate within the welt crease of a prewelt upper comprising side wipers, shank wipers, a toe wiper constructed and arranged to overwipe the entire toe portion of the welted margin, and forepart wipers constructed and arranged to be oriented by their engagement with the upper in the welt crease.

18. In a machine for use in the manufacture of prewelt shoes, a plurality of wipers constructed and arranged to operate within the welt crease of a prewelt upper comprising side wipers, shank wipers, and a toe wiper constructed and arranged to overwipe the entire toe portion of the upper, all of said wipers having a fixed orientation, and a pair of forepart wipers constructed and arranged to be oriented by their engagement with the upper in the welt crease.

19. In a machine for use in the manufacture of prewelt shoes, a plurality of wipers including a pair of forepart wipers constructed and arranged to operate within the welt crease of a prewelt upper, said wipers being normally so oriented that their rear end portions enter the welt crease in advance of their forward portions, said wipers during their continued advancement swinging about their rear end portions until they have been oriented relatively to the welted margin by their engagement with the upper.

20. In a machine for use in the manufacture of prewelt shoes, a forepart wiper constructed and arranged to operate within the welt crease of a prewelt upper, a carrier on which said wiper is mounted for turning movement on an axis intersecting its wiping edge, and yielding means for so orienting said wiper that its rear end portion enters the welt crease in advance of the forward portion of the wiper, the wiper during its continued advancement turning about the aforesaid axis until the wiper has been oriented by its engagement within the welt crease relatively to the periphery of the upper.

21. In a machine for use in the manufacture of prewelt shoes, a plurality of wipers constructed and arranged to operate within the welt crease of a prewelt upper including a pair of forepart wipers, a pair of shank wipers, and a pair of side wipers having straight wiping edges constructed and arranged to operate on that portion of the upper, extending rearwardly from the shank wipers, which lies within the range of the straight wiping edges of said wipers.

22. In a machine for use in the manufacture of prewelt shoes, a plurality of wipers constructed and arranged to operate within the welt crease of a prewelt upper comprising a toe wiper con-

structed and arranged to overwipe the entire toe portion of the upper, a pair of shank wipers, a pair of forepart wipers constructed and arranged to overwipe that portion of the upper lying between the toe wiper and the shank wipers, and a pair of side wipers having straight wiping edges constructed and arranged to overwipe that portion of the welted margin, extending rearwardly from the shank wipers, which lies within the range of wiping movement of the straight wiping edges of said wipers.

23. In a machine for use in the manufacture of prewelt shoes, means for supporting a prewelt upper off the last, a plurality of wipers constructed and arranged to operate within the welt crease, means for advancing the wipers into engagement with a portion of the upper adjacent to the welt crease, and means for moving said supporting means so to position an upper thereon that the wipers register with the welt crease.

24. In a machine for use in the manufacture of prewelt shoes, an inner form, a plurality of wipers constructed and arranged to operate within the welt crease, means for actuating said wipers to bring them into engagement with an upper on said form along a line adjacent to the welted margin, and means for moving said inner form and the upper thereon to cause said wipers to register with the welt crease.

25. In a machine for use in the manufacture of prewelt shoes, an inner form for supporting a prewelt upper off the last, a plurality of wipers constructed and arranged to operate within the welt crease, means for urging said wipers under relatively light pressure against the upper along a line adjacent to the welted margin, means for moving said inner form heightwise of the upper to cause said wipers to upwipe said upper and to be brought into registration with the welt crease, and means operating thereafter to apply relatively heavy overwiping pressure to said wipers.

26. In a machine for use in the manufacture of prewelt shoes, an inner form for supporting a prewelt upper by the inwardly extending portion of its welted margin, a plurality of wipers constructed and arranged to operate within the welt crease, a member on which said form is mounted, an actuator, connections from said actuator for first advancing said wipers and urging them under relatively light pressure against the upper along a line adjacent to the welted margin, then moving said member and the form thereon heightwise of the upper to cause the wipers to register with the welt crease and, finally, to apply relatively heavy pressure to said wipers to overwipe the welted margin.

27. In a machine for use in the manufacture of prewelt shoes, an inner form for supporting a prewelt upper off the last, an end wiper and a plurality of side wipers constructed and arranged to operate within the welt crease, an actuator for said end wiper, and an actuator constructed and arranged first to advance said side wipers and urge them under relatively light pres-

sure against the upper along a line adjacent to the welted margin, then to move said form heightwise of the upper to cause the wipers to register with the welt crease, and finally, to apply relatively heavy pressure to all of said wipers to overwipe the welted margin.

28. In a machine for use in the manufacture of prewelt shoes, an inner form for supporting a prewelt upper by its welted margin, a toe wiper, and a plurality of side wipers constructed and arranged to operate within the welt crease, an actuator for advancing said toe wiper and urging it under relatively light pressure against the toe portion of the upper along a line adjacent to the welt crease, a second actuator, connections from said actuator for first advancing the side wipers and urging them under relatively light pressure against the upper along a line adjacent to the welt crease, then moving said inner form heightwise of the upper to cause the toe wiper and the side wipers to register with the welt crease, and finally, applying relatively heavy overwiping pressure to the toe wipers and side wipers, means for holding said wipers in their respective overwiped positions, and means for releasing said holding means.

29. In a machine for use in the manufacture of prewelt shoes, an inner form for supporting a prewelt upper by its welted margin, a holder for said inner form, yielding means normally operating on said holder to maintain the inner form in an elevated position, a plurality of wipers constructed and arranged to operate within the welt crease, and an actuator for advancing said wipers and then moving said holder downwardly to cause the wipers to register with the welt crease of a prewelt wiper on said inner form.

30. In a machine for use in the manufacture of prewelt shoes, a plurality of wipers constructed and arranged to operate within the welt crease of a prewelt upper, said wipers including a pair of relatively narrow shank wipers and a pair of side wipers constructed and arranged to operate on opposite side portions of the upper extending heelwardly from the shank wipers, both said pairs of wipers having a fixed orientation, said side wipers being constructed and arranged to extend beyond the heel end of the upper to provide for their operation on a large run of sizes.

31. In a machine for use in the manufacture of prewelt shoes, a plurality of wipers constructed and arranged to operate within the welt crease of a prewelt upper, said wipers including a pair of relatively narrow shank wipers and a pair of side wipers constructed and arranged to operate on opposite side portions of the upper extending heelwardly from the shank wipers, both said pairs of wipers having a fixed orientation, said side wipers being constructed and arranged to extend in parallel relation to each other beyond the heel end of the upper to provide for their operation on a large run of sizes, and a common actuator for operating said wipers.

ERIC A. HOLMGREN.
